UNITED STATES PATENT OFFICE.

HORATIO E. COLLINS, OF DETROIT, MICHIGAN, ASSIGNOR OF ONE-HALF
TO J. H. HARRISON, OF DETROIT, MICHIGAN.

COAT AND HAT HOOK.

No. 811,380.

Specification of Letters Patent.

Patented Jan. 30, 1906.

Application filed August 19, 1905. Serial No. 274,849.

To all whom it may concern:

Be it known that I, HORATIO E. COLLINS, a citizen of the United States of America, residing at Detroit, in the county of Wayne and 5 State of Michigan, have invented certain new and useful Improvements in Coat and Hat Hooks, of which the following is a specification, reference being had therein to the accompanying drawings.

10 This invention relates to a hat and coat hook provided with a pivoted locking-arm arranged to be closed upon the hook to prevent the removal of a hat or coat placed upon the same except by the person holding the key to unlock the arm; and the invention consists in the construction, arrangement, and combination of parts whereby a cheap and practical device of this character is obtained, all as more fully hereinafter described, 15 and shown in the accompanying drawings, in which—

20

Figure 1 is an elevation of my improved hat and coat hook. Fig. 2 is another elevation of the same, taken from the opposite side 25 and shown on a smaller scale. Fig. 3 is a detached perspective view of the hook alone. Fig. 4 is a detached perspective view of the locking-arm, and Fig. 5 is a section on line *x* in Fig. 1.

30 *A* is the hook member, integrally cast with a back member *B* for attachment to a wall and with an enlargement forming the casing *C*.

D is the locking-arm, shaped to form a 35 counterpart of the hook with an enlargement *E* at its inner end which forms a cover for the casing *C*. In the center of this enlargement is an orifice *F*, and surrounding this orifice is a standing flange (or flanges) *H*, all so arranged that a lock, as *G*, preferably a common form of the Yale type of drawer-lock, 40 may be engaged with the enlargement, the keyhole-barrel of the lock projecting through the orifice, while the casing of the lock is held 45 in fixed position against rotation by the standing flange *H*.

The locking-arm is rotatively secured to the member *C* by means of two headed studs *I*, which pass loosely through slots *J* in the 50 enlargement *E* and are secured by rivet-heading into projections *K* upon the inner wall of the enlargement *C*, the studs *J* being shouldered where they pass into the projections.

Upon the inner wall of the enlargement is

cast a projection *L*, which is adapted to engage with the locking-bolt of the lock, and thereby hold the arm against rotation when in its closed position.

The operation of my device is obvious from the description, it being understood that the locking or unlocking of the arm *D* requires the use of the particular key fitted for the lock. It is in the particular arrangement and operation of this feature that my invention presents its particular novelty. 65 First, it will be seen that my invention obviates the necessity of devising or employing a particular form of lock, since many forms of ordinary commercial locks would be available, and I choose a Yale lock merely as being particularly well adapted for my purpose. My device can for this reason be constructed much cheaper than if it depended upon a lock of special construction. The aperture *F* is made to suit the keyhole in the 70 lock. By choosing a lock with a key-barrel and letting it project through it can be readily located in the dark, and it may or may not be in the pivotal center of the arm. It will further be observed that since the arm carries the lock the key in turning in the lock 75 will not only unlock the arm, but lift it, and when the arm is thus raised the key cannot be removed.

To identify each hook with its key, they 80 are correspondingly numbered, the hook having preferably the number cast upon an extension *M*.

While I have described my device as a "coat and hat hook," I use this term in a 85 general sense and include its use for locking up hand-satchels and other portable property of like character.

Having thus fully described my invention, what I claim is—

1. In a device of the character described, the combination of a fixed hook member adapted to be secured to the wall and provided with an enlargement at the base of the hook forming a casing, of a pivotal arm carried by the hook member and provided with an apertured enlargement at its inner end forming the cover for said casing, means rotatively connecting said cover to the casing, a lock of the character described inclosed in the casing and rotatively carried by the pivotal arm and a projection in the wall of the casing adapted to coöperate with the lock, 95 100 105

2. In a device of the character described, the combination of a fixed hook member integrally formed with a circular enlargement forming a casing, a pivotal arm carried by the hook and integrally formed with an enlargement forming a cover for the casing of the hook, means rotatively connecting said cover to the casing, a lock complete in itself loosely inclosed within the casing and rotatively held therein by suitable connection with the cover whereby the operation of the

key is adapted to operate the lock and oscillate the arm, and a locking projection on the inner wall of the casing coöoperating with the lock. 15

In testimony whereof I affix my signature in presence of two witnesses.

HORATIO E. COLLINS.

Witnesses:
